VENDING MACHINE

Roland T. Wright, St. Louis, Mo., assignor, by
mesne assignments, to Bick Corporation, a cor-
poration of Missouri

Application July 18, 1945, Serial No. 605,681

13 Claims. (Cl. 312—46)

1

This invention relates to a vending or dispensing machine for bottled goods or the like. Its intent is that the vending machine be coin-controlled, but the present invention does not relate to the coin-control mechanism.

The object of the invention is to provide a device for dispensing bottled goods such as soft drinks, or packaged goods of similar character, which will be simple in construction, efficient and positive in operation, and which will hold in its magazines a maximum amount of merchandise for the space employed.

Other and specific objects will be apparent from the following detailed description of a preferred embodiment of the invention. The drawings illustrate that preferred embodiment.

Fig. 1 is a front elevational view of the device; Fig. 2 is a front elevational view partly in section;

Fig. 3 is a horizontal section showing one, or the top, magazine taken on line 3—3, Fig. 1 but with some of the associated mechanism broken away or omitted for clarity;

Fig. 4 is a horizontal section showing means for moving the magazines step by step and taken on line 4—4, Fig. 1;

Fig. 5 is a detail showing the step by step moving mechanism on line 5—5, Fig. 4;

Fig. 6 is another view showing such mechanism on line 6—6, Fig. 4;

Figs. 7, 8 and 9 are further detail views showing such mechanism;

Fig. 10 is an elevational view showing the details of mechanism for delivering the bottles or merchandise from the magazine;

Fig. 11 is an elevational view showing in detail parts of the delivering mechanism;

Fig. 12 is a horizontal sectional view showing the delivery mechanism on line 12—12, Fig. 11, and

Figs. 13, 14 and 15 are plan views showing details of the device, and particularly the successive positions in the delivery of the merchandise.

The machine has a frame 1 comprising appropriate vertical and horizontal members. The mechanism is enclosed in a housing 2, which is preferably insulated since the device is intended primarily for dispensing bottled carbonated beverages maintained under refrigeration.

The device has two magazines, 3 and 4, on a common vertical axis, and connected by a sleeve 5 so that the two are rotated together step by step through a single mechanism, which later will be described in detail.

The two magazines are substantially alike, each

2

magazine having a series of radially extending compartments 6 surrounding its axis, each compartment as specifically shown being adapted to hold three bottles B in a row. Each compartment 5 has a partial bottom or provisional support 7, so arranged that there is sufficient space rearwardly, with respect to the direction of operational rotation, to permit the discharge of a bottle through the space. The arrangement is such that the bottom provisional support or bar 1 will support the outer bottle in the compartment when it is slightly inclined, but the bottle may be dislodged from the bar 1, and when so dislodged will fall through the space to the rear of the bar 7.

The arrangement of each compartment is such that the bottles on the outer circumferential row in the magazine have their tops tilted outwardly and rearwardly. It will thus be obvious that a bottle in such outer row may be displaced from the magazine and discharged if the bottom of the bottle is pushed rearwardly. In order to accomplish this result a fixed lug 8 is situated in the path of the bottles of the outer row adjacent a discharge chute 9. Then as the magazine is rotated a bottle in the outer row as it approaches the delivery station will successively strike the lug 8, which pushes the bottom of the bottle rearwardly and off the bar 7 so that the bottle will fall by its own weight through the space which has been provided to the rear of the bar. Further details of the construction of the magazines and their compartments will be given later.

It may now be understood that the magazine is rotated step by step so as to bring the bottles in the two magazines successively into contact with lugs 8, one for each magazine, so that the bottles will be discharged alternately from the two magazines, one bottle being discharged for each step of movement. For example, the specific embodiment illustrated in the drawings shows fourteen compartments in each magazine while the mechanism for moving the magazines contemplates a complete revolution of the magazines in twenty-eight steps, with each step sufficient to discharge one bottle.

The mechanism for moving the magazines step by step is best shown in Figs. 4 to 9 inclusive. A downwardly extending annular flange 10 is secured to the bottom 10a of the lower magazine 4 and has notches 11 for engagement by a pawl 12 and a latch 13, and thus functions as a ratchet. The pawl 12 is mounted on a lever 14, pivoted to an appropriate portion of the frame, and is movable on its pivot in a horizontal plane by a mechanical connection with a hand operated plunger

15. This connection includes a link 16, connected to the plate or lever 14, a lever 17 connected with the link 16, and a bar 18. The bar 18 is connected with the plunger 15 by means which are not shown in detail but which preferably include coin or check controlled apparatus, which may be any one of many devices known in the art. It will be understood, however, that by pulling the plunger 15 the pawl 12 and its assembly may be moved back and forth.

During times of rest the magazines are locked in position by the latch 13 engaging in a notch 11. Means are provided for releasing the latch 13 incident to movement of the pawl. This means includes a cam 19 mounted on the pawl plate 14 and moving with the pawl, and a lever 20 engaging the latch 13. Here the connection between the lever 20 and the latch 13 is made by passing an end 20a of the lever through a hole 13a in the latch. The lever 20 is a lever of the first class pivoted on an appropriate cross member 21 of the frame, and has a lug 22 for engagement by the cam 19.

Fig. 8 illustrates the position of the actuating mechanism at the beginning of the stroke. The initial part of the stroke serves to disengage the latch 13. Rearward movement of the pawl assembly, including its plate 14 and the cam 19 (from the position shown in Fig. 8 to the position shown in Fig. 9) brings the upper surface of the cam 19 into engagement with the lug 22 forcing it upward and the opposite end of the lever 20 downward, to lower the latch 13 out of engagement with the notch 11. The pawl 12 has by this time reached and engaged a notch 11 the same being moved into engagement therewith by a spring 12a, and the apparatus is in the position shown in Fig. 9. Further movement of the pawl assembly will rotate the magazines. As soon as the cam 19 is past the lug 22, as it is about to be in the position shown in Fig. 9, the latch 13 will be released and will return upwardly under the influence of a spring 23, attached to the outer end of the lever 20, and rest against the lower edge of the flange 10 until the next notch 11 reaches it, at which time it will spring into latching position.

The cam 19 is pivotally supported so that on the return stroke it will ride over the lug 22, as shown in Fig. 7.

A spring 24 is attached between the plate 14 and a member of the frame 1, and performs the return stroke of the pawl assembly.

It will now be understood that upon pulling the plunger 15, the pawl assembly will be advanced first to lower the latch 13 by action of the cam 19 against the lug 22, and then, by the pawl 12 engaging in a notch 11, to advance the magazines one step until the latch engages in a succeeding notch and stops the movement; whereupon the spring 24 causes the return movement of the pawl assembly.

Means are provided for manually releasing the latch and the pawl, so that the magazines may be turned freely as is desired in loading or servicing the magazines. This includes a plunger 30 connected to a lever 31, which has a cam 32 positioned to engage a projection 33 on the latch 13. Thus when the plunger 30 is pulled the cam 32 slides over the projection 33 to depress the latch 13. An arm 34 is fastened to the outer end of the latch 13 and is so positioned that it will engage and depress the pivoted pawl 12. Thus when the lever 30 is pulled out the latch and the pawl are disengaged and held disengaged from

the flange 10, permitting the magazines to be freely rotated.

As previously explained, each of the magazines 3 and 4 includes a series of radially disposed compartments so arranged that each compartment as specifically shown holds three bottles. Thus the magazine has a capacity to carry three annular rows of bottles. While the compartments are disposed generally radially about the axis of the magazine, they are curved rearwardly with reference to the direction of operational rotation. The sides of the compartments are formed by plates 35 which are secured to the bottom 10a of the magazine and to a ring-like member 35a (see Figs. 3 and 10) supported on the said bottom and the ends are curved straps 36. These plates are notched at 35b to permit a bottle positioning lug, later to be described, to pass the ends thereof. The bottom of each compartment comprises the bar 7 which slants downwardly towards the periphery of the magazine. The arrangement of the bar 7, which is passed through and secured to the member 35a and to the bottom 10a, is such that it supports the inner and intermediate bottle and supports the outer bottle when in a slanting position. But it is so arranged with reference to the outer portion of the compartment that a space is provided to the rear of the bar sufficient to permit the discharge of a bottle therethrough when the bottom of the bottle is shoved off the bar 7. It has already been explained that a bottle in the outer row is shoved off the bar 7 by the lug 8 as the magazine is rotated step by step.

35 The construction of the magazines and their compartments is such that when a bottle is discharged the other bottles in the compartment will, under favorable conditions and due to the slope of the bar 7 and centrifugal force, move outwardly. Nevertheless means are provided to positively move the bottles outwardly as the magazine is rotated. An overhanging arm 37 is adapted to engage the shoulder of the intermediate bottle immediately after the outer bottle has been discharged and push said intermediate bottle outwardly, while a lug 38 is positioned to engage the bottom of the inner bottle and push it outwardly at about the same time or immediately following.

50 To assist in the smooth operation of the device the head of the intermediate bottle is engaged by a support or rail 39 which supports the head of that bottle while the outer bottle is being discharged.

55 The action in the movement of the bottles is illustrated in Figs. 10, 13, 14 and 15.

Fig. 10 is an elevational view which shows the lug 8 engaging the bottom of the bottle at the same time that the head of the intermediate bottle is supported by the rail 39, and as the arm 37 is engaging the shoulder of the intermediate bottle and just as the lug 38 is engaging the bottom of the inner bottle.

Fig. 13 shows the arrangement of the bottles as a compartment is approaching the delivery station.

Fig. 14 is a plan view of the bottles in approximately the same position as Fig. 10. Here the lug 8 is engaging the bottom of the outer bottle and about to push it off the support 7, while the head of the intermediate bottle is supported by the rail 39 and the arm 37 is engaging the shoulder of the intermediate bottle. The inner bottle is approaching and about to engage the lug 38.

70 In Fig. 15 the bottle which was in the inter-

mediate position has now assumed a position at the outer end of the compartment and the lug 38 has shoved the remaining bottle to the intermediate position.

It may be understood that on the next revolution another bottle will be discharged and on the following revolution the last bottle will be discharged from the compartment.

It will be understood, of course, that the devices which have been described as pertinent to a magazine are provided separately for each magazine 3 and 4. The bottles discharged from the top magazine 3 pass through the tubular chute 9 and then into a lower chute 40, which has an elongated mouth and in which the bottles from the lower magazine 4 are discharged directly. The chute 40 discharges through a convenient outlet or door 41 in the cabinet. Moreover, the device is arranged to successively discharge the goods from the magazines 3 and 4 alternately. Thus, the vertical alignment of the two magazines and the vertical alignment of the lugs 8 (see Fig. 11) are such that at one step in the movement of the magazines the top lug 8 will dislodge a bottle from the top magazine and at the next step the bottom lug 8 will dislodge a bottle from the bottom magazine. Since it is desirable to discharge bottles from the two magazines at slightly different points, one into the chute 9 and the other into the lower chute 40, as described, the two magazines are slightly out of alignment to permit their discharge on slightly different vertical lines. But the two lugs 8 are also disaligned in the specific embodiment as shown.

To provide for easy loading of the magazine, special means are provided moving out of the way the devices which engage the bottle and for releasing and holding the magazine latch and pawl. The two sets of lugs 8, the arms 37, and rails 39, and the chute 9 for the upper magazine are all supported on a common rack 42, which is hinged on a vertical axis to appropriate members of the frame 1. Here, the chute 9 is attached to the rack by two brackets 9a. Thus the rack with these appurtenances may be moved entirely out of the way when the magazines are to be refilled or otherwise serviced. This rack is held in position by a latch 43. When the latch 43 is released the rack and its assembly may be swung out of engaging position. Then when the plunger 30 is pulled, the latch 43 and the pawl 12 are disengaged from the magazines. Then the magazines may be turned freely, except for the inner lug 38 which engages the inner row of bottles. That lug 38 is attached to the bottom of a pivoted arm 44 which is biased by a spring 44a (Fig. 2). The lug 38 has a cam surface 38a on its forward side, so that the arm 44 will pivot and the lug 38 will be pressed out of the way by the inner bottles when the magazines are rotated in a clockwise direction or a direction opposite to its operational one. The arrangement described in this paragraph provides for free turning of the magazines for loading but in a direction counter to the operational direction.

The cabinet is provided with a door 50 for access to the magazines. It is also provided with a discharge door 41 previously mentioned, and with a fitting 51 through which projects the operational handle or plunger 15. The cabinet is also provided with a fitting 52 for the coin-controlled apparatus.

Space in the bottom of the cabinet may be used for a refrigerating coil and a storage space for precooled bottles, while the extreme bottom

of the cabinet may provide for refrigerating apparatus including a compressor and motor. Louvers 53 are shown to provide ventilation and cooling for the motor and compressor unit.

5. It will be obvious that since merely a preferred embodiment of the device is illustrated and described, various changes may be made in the details of construction within the scope of the appended claims, without departing from the spirit 10 of this invention. Parts of the invention may be used without the whole, and improvements may be added thereto, while retaining the benefits of the invention.

1. claim:

15. 1. A vending machine for bottled goods or the like including a magazine mounted for rotation about a vertical axis, said magazine having a series of radially extending compartments, surrounding its axis, a bottom support member for each compartment arranged with respect to side walls of the compartment to support the goods in a substantially vertical position such that the tops of the goods will lean rearwardly with respect to the direction of rotation of said magazine, and means for moving the goods to a vertical and unsupported position causing their discharge from the magazine, said means being operable upon rotation of the magazine, whereby the goods may be discharged from the magazine upon step by step rotation of the magazine.
20. 2. A vending machine for bottled goods or the like including a magazine mounted for rotation about a vertical axis, said magazine having a series of radially extending compartments surrounding its axis, each compartment having side walls and a bottom support arranged with respect to said side walls to provide open spaces in the bottom of each compartment rearwardly of each support with respect to the direction of rotation of said magazine, said spaces being provided to permit the discharge of goods therethrough, a fixed lug in the path of the goods positioned and arranged to shove the goods off the supports and thereby discharge them by permitting them to drop through said spaces from the magazine as they severally contact the lug upon rotation of the magazine, and means for rotating the magazine step by step to singly and successively discharge the goods from the magazine.
25. 3. A vending machine for bottled goods or the like including a magazine mounted for rotation about a vertical axis, said magazine having a series of radially extending compartments surrounding its axis, each compartment being proportioned to contain a plurality of bottles whereby the magazine accommodates a plurality of concentric rows of bottles, each compartment having a partial bottom providing a provisional support so arranged that there is sufficient space
30. 49. 5. rearwardly with respect to the direction of rotation to permit the discharge of bottles therethrough, a fixed lug in the path of the bottles in the outer row positioned and arranged to shove the bottles off the supports and thereby discharge them by causing them to drop from the magazine as they severally contact the lug upon rotation of the magazine, means for engaging the remaining bottles in a compartment to cause them to move outwardly along the support as the outer bottle is discharged, and means for rotating the magazine step by step to singly and successively discharge the bottles from the magazine.
55. 60. 6. A vending machine for bottled goods or the like including a magazine mounted for rotation about a vertical axis, said magazine having a

70. 75. 7. A vending machine for bottled goods or the like including a magazine mounted for rotation about a vertical axis, said magazine having a

series of radially extending compartments surrounding its axis, each compartment being proportioned to contain a plurality of bottles whereby the magazine accommodates a plurality of concentric rows of bottles, each compartment having a partial bottom providing a provisional support so arranged that there is sufficient space rearwardly with respect to the direction of rotation to permit the discharge of bottles therethrough, a fixed lug in the path of the bottles in the outer row position and arranged to shove the bottles off the supports and thereby discharge them by permitting them to drop from the magazine as they severally contact the lug upon rotation of the magazine, the said provisional bottom sloping downward from axis to periphery thereby permitting the remaining bottles in a compartment to move outwardly along the bottom as the outer bottle is discharged, and means for rotating the magazine step by step to singly and successively discharge the bottles from the magazine.

5. A vending machine for bottled goods or the like including a magazine mounted for rotation about a vertical axis, said magazine having a series of radially extending compartments surrounding its axis, each compartment being proportioned to contain a plurality of bottles whereby the magazine accommodates a plurality of concentric rows of bottles, each compartment having a partial bottom providing a provisional support so arranged that there is sufficient space rearwardly with respect to the direction of rotation to permit the discharge of bottles therethrough, a fixed lug in the path of the bottles in the outer row positioned and arranged to shove the bottles off the supports and thereby discharge them by permitting them to drop from the magazine as they severally contact the lug upon rotation of the magazine, a fixed rail in the path of the bottles in the second row positioned to partially support a bottle while the adjacent bottle in the outer row is being engaged by said fixed lug, and means for rotating the magazine step by step to singly and successively discharge the bottles from the magazine.

6. A vending machine for bottled goods or the like including a magazine mounted for rotation about a vertical axis, said magazine having a series of radially extending compartments surrounding its axis, each compartment being proportioned to contain a plurality of bottles whereby the magazine accommodates a plurality of concentric rows of bottles, each compartment having a partial bottom providing a provisional support so arranged that there is sufficient space rearwardly with respect to the direction of rotation to permit the discharge of bottles therethrough, a fixed lug in the path of the bottles in the outer row positioned and arranged to shove the bottles off the supports and thereby discharge them by permitting them to drop from the magazine as they severally contact the lug upon rotation of the magazine, a normally fixed member for engaging and moving a remaining bottle outwardly after the outer bottle in the same compartment is discharged, and means for rotating the magazine step by step to singly and successively discharge the bottles from the magazine.

7. A vending machine for bottled goods or the like including a vertical spindle, two magazines fixed on and rotated by the spindle, each magazine having a series of radially extending compartments surrounding the spindle, each compartment having side walls and a bottom support

arranged with respect to said side walls to provide open spaces in the bottom of each compartment rearwardly of each support with respect to the direction of rotation of said magazines, said spaces being provided to permit the discharge of goods therethrough, fixed lugs respectively in the path of the goods in the compartments to shove the goods off the supports and thereby discharge them by permitting them to drop through said spaces from the magazines as they contact the lugs upon rotation of the magazines, and means for rotating the magazines step by step to singly and successively discharge the goods from the magazines alternately.

15 8. A vending machine for bottled goods or the like including a magazine mounted for rotation about a vertical axis, said magazine having a series of radially extending compartments surrounding its axis, each compartment having side walls and a bottom support arranged with respect to said side walls to provide open spaces in the bottom of each compartment rearwardly of each support with respect to the direction of rotation of said magazine, said spaces being provided to permit the discharge of goods therethrough, a fixed lug in the path of the goods positioned and arranged to shove the goods off the supports and thereby discharge them by permitting them to drop through said spaces from the magazine as they severally contact the lug upon rotation of the magazine, and a ratchet and pawl for rotating the magazine step by step to singly and successively discharge the goods from the magazine.

35 9. A vending machine for bottled goods or the like including a magazine mounted for rotation about a vertical axis, said magazine having a series of radially extended compartments surrounding its axis, each compartment having side walls and a bottom support arranged with respect to said side walls to provide open spaces in the bottom of each compartment rearwardly of each support with respect to the direction of rotation of said magazine, said spaces being provided to permit the discharge of goods therethrough, a normally fixed lug in the path of the goods positioned and arranged to shove the goods off the supports and thereby discharge them by permitting them to drop through said spaces from the magazine as they severally contact the lug upon rotation of the magazine, means for rotating the magazine step by step to singly and successively discharge the goods from the magazine, and a hinged support for the lug permitting it to be moved out of engaging position so that the magazine may be turned without discharging goods.

60 10. A vending machine for bottled goods or the like including a magazine mounted for rotation about a vertical axis, said magazine having a series of radially extending compartments surrounding its axis, each compartment being proportioned to contain a plurality of bottles whereby the magazine accommodates a plurality of concentric rows of bottles, each compartment having a partial bottom providing a provisional support so arranged that there is sufficient space rearwardly with respect to the direction of rotation to permit the discharge of bottles therethrough, a lug normally fixed in the path of the bottles in the outer row positioned and arranged to shove the bottles off the bottoms and thereby discharge them from the magazine as they severally contact the lug upon rotation of the magazine, a device for moving said bottles along said

provisional support normally fixed in a position to engage bottles in the second row, means for rotating the magazine step by step to singly and successively discharge the bottles from the magazine, and a hinged support for said device permitting it to be moved out of engaging position so that the magazine may be turned without interference from said device.

11. A vending machine for bottled goods or the like including a magazine mounted for rotation about a vertical axis, said magazine having a series of radially extending compartments surrounding its axis, each compartment being proportioned to contain a plurality of bottles whereby the magazine accommodates a plurality of concentric rows of bottles, each compartment having a partial bottom providing a provisional support so arranged that there is sufficient space rearwardly with respect to the direction of rotation to permit the discharge of bottles therethrough, a lug normally fixed in the path of the bottles in the outer row positioned and arranged to shove the bottles off the bottoms and thereby discharge them from the magazines as they severally contact the lug upon rotation of the magazine, a device for moving said bottles along said provisional support normally fixed in a position to engage bottles in the second row, means for rotating the magazines step by step to singly and successively discharge the bottles from the magazine, and a hinged support carrying said lug and said device permitting them to be moved

out of engaging position so that the magazine may be turned without interference from them.

12. In a vending machine for bottles goods or the like having a magazine mounted for rotation about a vertical axis, means for rotating the magazine step by step to singly and successively discharge goods from the said magazine comprising a ratchet fixed to rotate with said magazine, a latch engagable with said ratchet to hold

5 10 said magazine against rotation, a spring biased, cam operated lever for releasing said latch and a spring biased pawl engagable with said ratchet for rotating said magazine, said lever and said pawl being movable to perform their desired functions by a coin controlled manually operated plunger.

15 13. Apparatus as claimed in claim 12 including means for holding said latch and said pawl out of engagement with said ratchet whereby said magazine may be rotated freely.

20 ROLAND T. WRIGHT.
